UNITED STATES PATENT OFFICE.

LYMAN T. SMITH, OF NEW HAVEN, CONNECTICUT.

DIE FOR FORMING CARRIAGE-CURTAIN LOOPS.

SPECIFICATION forming part of Letters Patent No. 269,240, dated December 19, 1882.

Application filed October 15, 1881. Renewed May 10, 1882. (No model.)

To all whom it may concern:

Be it known that I, LYMAN T. SMITH, a citizen of the United States, residing at New Haven, in the county of New Haven and State of Connecticut, have invented new and useful Improvements in Dies for Forming Carriage-Curtain Loops, of which the following is a specification.

Hitherto patent-leather loops for carriage-curtains have been made by holding the leather with the bands upon a bed "former," and by a suitable hand - tool press and crimp the leather over and around the base of the former to give form to the loop, and then using the tool to press and work the leather into the ornamenting grooves in the face of the former, both the forming and the ornamenting operations being effected by hand, rendering the work slow and the loops more or less imperfect in the crimping and in the ornamentation. The usual way of producing carriage-curtain loops of harness-leather by dies would not answer for producing such loops of patent-leather, because it would crack and be cut under the crimping and embossing action; but as a patent-leather finish to the loop gives a better finish to the curtain and is better suited for fine work it is important that the cost of their production be reduced as much as possible and the crimp and ornamentation be rendered permanent. This I effect by the operation of dies in which a removable cushion or yielding supporting-surface and a crimping-plate are used, the latter to give the crimp and form to the loop over the matrix and the cushion to give a fullness to that portion of the loop which is above the face of the matrix, these two things being effected in the operation of crimping the loop and before the action of the die to give the ornamentation to the loop, the accomplishment of which is only rendered possible without cracking or splitting the loop by the withdrawal of said cushion to form a space between the under side of the loop and the face of the matrix before such action of the die or stamp. This fullness is formed in the loop within the opening in the crimping-plate, and the action of the die takes up this fullness in the grooves or depressed surfaces of the matrix in embossing or ornamenting the loop and in completing the crimp of the embossed surface. This fullness therefore forms an equivalent for the

leather required to make the embossed surface, and it is this equivalent material which prevents the cutting of the loop along the edges 55 of the matrix, and which would result from the drawing action of a die upon patent-leather were it drawn tightly over the matrix when receiving such die action.

Referring to the accompanying drawings, 60 Figure 1 represents in perspective dies embracing my improvements for producing patent-leather loops for carriage-curtains, the loop being shown as having been formed under the operation of the crimping-plate and upon the 65 cushion which gives fullness to said loop above the matrix; Fig. 2, a similar view, the die and crimper parts having the same relation to each other, but showing the cushion removed and the fullness given to the loop thereby; Fig. 3, 70 a similar view, showing the die proper in position to emboss and complete the loop; Fig. 4, an end view, the die parts shown as in Fig. 3; Fig. 5, a vertical longitudinal section of Fig. 1; Fig. 6, a similar sectional view of Fig. 3; Fig. 75 7, the removable cushion; Fig. 8, the formed and embossed loop; and Fig. 9, the matrix or bed, showing the depressed edge surface or 80 rabbit for the lapped edge of the loop.

The loops are formed with one end pointed 80 and closed, and are adapted to receive and inclose the fastening-straps of carriage-curtains. The matrix or bed *a* has the required form and surface mold, and the die *b* is of corresponding form, and has a raised surface matching the 85 matrix. These two parts are preferably of copper, to prevent corrosion, and are secured to carrying-plates suitable for the purpose. A plate, *c*, formed with an opening, *d*, corresponding to the shape of the matrix, is adapted 90 to receive the latter, and constitutes the crimper. The depth of the opening *d* in said plate is greater than the projection or height of the matrix therein, and the width of the latter sufficiently less than that of said opening to 95 allow the leather being formed into the loop to be pressed by the crimper over the sides of said matrix, while the sides of said crimper-opening diverge toward the base of the matrix, whereby the latter and the said plate *c* co-operate to receive and crimp the leather and give form to the loop by pressure applied to the crimper by a press or otherwise, as shown in Fig. 1. In this operation the loop is crimped 100

and formed over a cushion, *e*, of leather, india rubber, or other suitable material, placed upon the matrix, so that upon the withdrawal of the cushion a fullness is left in the loop above the matrix equal to the thickness of the cushion. It is this fullness that prevents the cutting of the loop in the operation of embossing and completing the loop by the die, which is then brought into action upon the loop by a press or otherwise. In this action of the die its raised surfaces will take up the fullness in the loop without drawing the leather tight over the edges of the matrix. In fact, the edges of the loop will be given a slight fullness over the edges of the matrix in the embossing operation, in which the die enters the opening *d*, leaving a space around its sides. The matrix and the die enter nearly equally within the opening in the crimpler, and the die-plate and the matrix-plate are provided with guide-pins *g*, which enter corresponding holes, *h*, in the crimpler-plate to insure the proper matching of the parts. The square ends of the die and of the matrix are preferably even with the end of the crimpler-plate, and the opening *d* at said end allows the cushion to be withdrawn from the crimped loop, as stated. The piece of leather to form the loop must be large enough to leave a margin for the presser-foot of the sewing-machine in sewing the loop to the curtain, and this margin is clamped by the crimpler upon the matrix-plate in forming the loop.

Bordering the front edge of the matrix-plate, and extending over the sides and top of the front end of the matrix, is a depressed surface part or rabbet, *i*, such depression being equal to the thickness of the leather, and within and along such depression the turned-in edge of the loop lies to allow of a uniform pressure and crimping of the loop around the base of the matrix.

To form the loop the cushion is placed upon the matrix, the piece of leather dampened, placed upon and slightly crimped by hand over the cushion. The crimpler-plate is then placed upon its guide-pins and over the leather, so as to receive it within the opening *d*, the parts thus united being then put in a press and the crimpler-plate forced down to crimp and form the loop over the cushion. The united parts are then removed from the press, the cushion pulled out by taking hold of the projecting ends *e'*, and the die by its guide-pins is properly placed upon the loop, and pressure applied to emboss it and to finish the crimping of the loop. The die and crimpler-plate and loop are then removed and the operation repeated in the production of loops from patent-leather in an expeditious manner. After the

loop is formed it is stiffened by any suitable varnish applied to its inner surface. The surplus margin is trimmed around the edge after the loop is sewed to the curtain. The matrix and die are so formed as to give the embossed surface of the loop a taper to its closed end.

The cushion is preferably of harness-leather, has a slight surface taper to its point, and a cross-notch on its under side near its outer end to gage its position upon the matrix.

Although I have described the manufacture of carriage-curtain loops of patent-leather in connection with a removable cushion used in the crimping operation, it is obvious that loops of harness-leather may be made without the use of the cushion in the crimping operation.

I claim—

1. For making leather loops for carriage-curtains, the combination, with the die, the crimpler-plate, and the matrix or bed, of a removable cushion having the form of the loop, held in place and used, substantially as described, for the purpose specified.

2. The combination of the die *b* and the matrix or bed *a* with a crimpler-plate, *c*, having an end opening, *d*, and a removable cushion, *e*, having a hand-hold and adapted for use with the matrix or bed, substantially as described, for the purpose specified.

3. The matrix *a* and its bed-plate having a depressed surface or rabbet, *i*, at the front end, in combination with the crimpler-plate *c*, having the end opening, *d*, the die *b*, and the removable cushion *e*, all constructed and adapted for operation, substantially as described, for the purpose specified.

4. The combination of the die *b* and the matrix *a* with the crimpler-plate *c*, having an end opening, *d*, adapted to receive the matrix in the operation of crimping the loop and the die in the subsequent operation of embossing or ornamenting the surface and finishing the loop, substantially as described.

5. The process of making leather loops for carriage-curtains, consisting in first crimping the leather blank and partially forming the loop portion over a yielding supporting surface, then removing such yielding supporting surface and completing the forward ornamentation of such loop upon a rigid matrix, substantially as set forth.

In testimony whereof I have hereunto set my hand in the presence of two subscribing witnesses.

LYMAN T. SMITH.
